UNITED STATES PATENT OFFICE.

FANNIE HEIN, OF NEW YORK, N. Y.

TELEPHONE ATTACHMENT.

1,217,445.

Specification of Letters Patent. Patented Feb. 27, 1917.

Application filed December 9, 1915. Serial No. 65,920.

To all whom it may concern:

Be it known that I, FANNIE HEIN, a citizen of the United States, and a resident of New York city, in the county of New York and State of New York, have invented certain new and useful Improvements in Telephone Attachments, of which the following is a specification.

This invention relates to attachments for telephones, and has particular reference to the mode of supporting the telephone receiver.

In the use of the telephone, considerable inconvenience is often caused by reason of a person being compelled to hold the receiver to his ear during a long conversation which is often very fatiguing. This is particularly true when the wire has to be held waiting for the person at the other end of the line, thus causing not only annoyance but also loss of time as the person holding the receiver in one hand cannot very well do anything else while he is waiting.

One object of the present invention is, therefore, to provide means whereby the telephone receiver may be supported in the proper position adjacent the ear of the person talking into the transmitter, thus leaving his hands entirely free to do other things while he is waiting for his party.

Another object is to provide movable means of this character which may operate to depress the receiver hook when the telephone is not in use.

A still further object is to lock the telephone receiver hook so as to prevent accidental raising thereof.

The various further objects and advantages will more fully appear from the detailed description and the features of novelty residing in the novel construction and combination of elements will be particularly pointed out in the claims.

In the drawing illustrating a few embodiments of the invention,

Figure 1 is a front elevation, and Fig. 2 is a side elevation, partly in section, of the improved attachment, with a bracket of the lazy-tong type.

Fig. 3 is a fragmental side elevation, partly in section, illustrating the bracket as extended.

Referring in detail to the drawings, particularly to Figs. 1, 2 and 3, the improved attachment may be secured to the telephone

instrument at any suitable point, as at the neck portion 10, by a suitable clamp 11. Extending from the clamp is a supporting arm 12 on which is pivoted the extensible lazy-tong bracket 13. On the forward end 60 of the bracket, means are provided for supporting the telephone receiver in position adjacent the ear of the speaker when he is talking into the receiver. Thus, the end link 14 of the bracket may be bent over to 65 form a substantially horizontal support 15 on which is preferably swiveled at 15 a socket or clip member 16. The latter is formed with the spring arms 17 which grip the cylindrical body of the receiver and hold 70 it normally in position at right angles to the axis of the mouth piece of the transmitter.

It will be noted that the supporting arm 12 of the bracket extends outward away from the instrument, thus supporting the 75 extensible bracket and the receiver in such spaced position relative to the telephone instrument as corresponds to the distance between the plane of the ear and the mouth of the average person. Thus, when the bracket 80 is extended and the person assumes a natural position talking into the transmitter, his ear will be directly against the mouth of the receiver in proper position for listening. However, by reason of the extensibility of 85 the bracket as well as the pivoting of the holding socket upon the bracket, any adjustment may be made suitable to the individual requirements of the person using the telephone.

One of the advantageous features of the invention resides in the means whereby the simple movement of the bracket in contracted position, automatically depresses and locks the receiver hook while the movement of the bracket into extended or operative position unlocks the receiver hook and permits the same to rise under the impulse of the usual spring provided for that purpose. This is preferably accomplished as 100 follows:

The rear arm 18 of the lazy-tong bracket is formed with an extension 19 to which is attached a cam 20 in position to engage the receiver hook 21. When the bracket 13 is contracted, as in Fig. 2, the high portion of the cam engages the receiver hook and depresses the same into inoperative position and holds the same locked in that position. When the bracket is extended, as in Fig. 3, 110

the low portion of the cam 20 is swung over the receiver hook, permitting the latter to rise into operative position. Thus, the natural act of a person using the telephone to pull the receiver to his ear or push it away, will automatically operate the receiver hook and hold it in locked inoperative position or in operative position. If desired, a hook 22 may be formed upon a suitable forward link 10 of the bracket for easily grasping the same, whereby the bracket may be readily manipulated.

For counterbalancing the weight of the receiver, especially when in extended position, a weight member 23 may be attached, as by a clamp 24, at a suitable point, preferably at the base of the instrument, in a position opposite from the receiver bracket, and this weight may be made in the form of a 20 pad holder 25 on which sheets may be kept to take down memoranda while talking at the telephone. If desired, also a pencil rack 26 may be formed in the pad holder.

I have illustrated my invention as applied to the usual portable desk instrument. However, it will be understood that it may be applied with equal advantage to the box instrument attached to the wall. While I have described several modifications of the invention, it will be understood that various further modifications may be resorted to without departing from the spirit of the invention and the scope of the claims.

Having thus described my invention, I claim as new and desire to secure by Letters Patent:

1. An attachment for telephones comprising a movable support for holding the telephone receiver, said support being movable to an operative position wherein the mouth of the receiver is adjacent to the ear of a person talking into the telephone transmitter, means associated with said attachment whereby the receiver hook is depressed when the support is returned to its normal or inoperative position, and means attachable to the base of the telephone instrument on the side opposite to the receiver for counterbalancing the weight of the receiver when

the support is moved into operative position.

2. An attachment for telephones comprising a supporting member adapted to be attached to the telephone instrument, an extensible lazy tong bracket mounted on said supporting arm, a socket for holding the telephone receiver mounted on said bracket, and means actuated by the bracket during its contraction to lock the receiver hook in 60 inoperative position.

3. An attachment for telephones comprising a supporting member adapted to be attached to the telephone instrument, an extensible lazy tong bracket pivoted on said 65 supporting member, a cam arm connected with the lazy tong bracket and located above the telephone receiver, and means for holding the telephone receiver on the bracket, said cam arm operating to depress 70 and lock the receiver hook in inoperative position when the lazy tong bracket is contracted.

4. An attachment for telephones comprising a supporting member adapted to be attached to the telephone instrument, an extensible lazy tong bracket mounted on said supporting arm, a socket for holding the telephone receiver swiveled on said bracket, and means actuated by the bracket during 80 its contraction to lock the receiver hook in inoperative position.

5. An attachment for telephones comprising a supporting member adapted to be attached to the telephone instrument, an extensible lazy tong bracket mounted on said supporting arm, a socket for holding the telephone mounted on said bracket, means actuated by the bracket during its contraction to lock the receiver hook in inoperative position, and a hook at the forward 90 portion of the bracket for readily grasping the same to extend the bracket.

Signed at New York city, in the county of New York, and State of New York, this 95 17th day of November, A. D. 1915.

FANNIE HEIN.
